UNITED STATES PATENT OFFICE.

CHARLES W. LOVELL, OF WILKINSBURG, PENNSYLVANIA, ASSIGNOR TO WESTINGHOUSE ELECTRIC & MANUFACTURING COMPANY, A CORPORATION OF PENNSYLVANIA.

IGNITION AND LIGHTING SWITCH.

Application filed January 13, 1922. Serial No. 528,986.

To all whom it may concern:

Be it known that I, CHARLES W. LOVELL, a citizen of the United States, and a resident of Wilkinsburg, in the county of Allegheny and State of Pennsylvania, have invented a new and useful Improvement in Ignition and Lighting Switches, of which the following is a specification.

My invention relates to ignition and lighting switches such as are commonly employed for controlling the ignition and lighting circuits of automobiles and other motor vehicles.

One object of my invention is to provide an arrangement for automatically locking switch members in predetermined positions upon their actuation to such positions.

A second object of my invention is to provide an arrangement whereby a single locking mechanism may operate to lock each of a plurality of switch members in one or more positions, as desired.

A further object of my invention is to provide a locking mechanism for a plurality of switches whereby the locking mechanism may be actuated to operative position at any desired time without interfering with the operation of the switches until they are actuated to predetermined positions in which it is desired to retain them.

A switch mechanism constructed in accordance with my invention comprises broadly an ignition and a lighting switch and a single mechanism for locking them.

The locking mechanism is so arranged that, upon its actuation to its operative position, the locking bolts are yieldable in case corresponding recesses in the switch members do not register with the bolts. In such event, the switches are automatically locked when they are actuated to predetermined positions.

The details of my invention will be described in connection with the accompanying drawing, in which

45 Figure 1 is a front elevational view of a switch embodying my invention.

Fig. 2 is a front view, partially in elevation and partially in section of the switch of Fig. 1, the cover member being removed.

50 Fig. 3 is a view in longitudinal section taken on line III—III of Fig. 1.

Figs. 4, 5 and 6 are respectively side elevational, top and end views of the bolt mechanism of the lock.

My improved switch mechanism comprises a base plate 1 of suitable insulating material, a cover member 2 of cup shape and a front plate member 3 that is inset in the cover member 2. The ignition switch comprises a cylindrical contact drum 4 that is mounted upon a shaft 5 provided with an operating handle 6. The contact drum 4 coacts with stationary contact fingers 7, 8 and 9 that are suitably secured to the base plate 1.

The lighting switch comprises a contact drum 10 mounted upon a shaft 11 and controlled by an operating handle 12. Stationary contact members 13, 14, 15 and 16 coact with the contact drum 10.

A lock mechanism 17 comprises the usual key barrel 18 which has secured thereto at the rear end thereof a pawl member 19 provided with an extending arm 20. The lock mechanism comprises, also, a bolt mechanism 22 that is reciprocable in a groove 23 in the base plate 1. The bolt mechanism comprises a casing member 24 of substantially rectangular shape that is provided with a pin 25 for coacting with the arm 20 of the pawl 19. At each end of the casing 24 is slidably mounted a bolt 26 for coacting with corresponding recesses 27 in disks 28 that are secured to the respective shafts 5 and 11.

The several notches 27 register with the corresponding bolts 26 preferably when the ignition switch is in its "Off" position only and the lighting switch is in any of the positions designated "Off", "Rear" and "Aux. Rear". It will, of course, be understood that the switches may be locked in any of their several positions by providing notches 27 to correspond to such positions. Each of the bolts 26 is yieldingly maintained in its extended position by a spring 30.

The operation of the switches during the normal operation of the vehicle in connection with which it is employed may be readily understood. The bolt mechanism 22 normally occupies its inoperative position in which it is illustrated in Figs. 2 and 3. In case it is desired to lock the switches

in certain positions, the switches may be actuated to such positions prior to the operation of the lock mechanism. When the key is turned to actuate the bolt mechanism, the 5 bolts 26 project into the corresponding recesses 27, and rotation of the switch drums is thereby prevented.

In case, however, it is desired, for any 10 reason, to remove the key prior to the actuation of the switches to the positions in which they are to be locked, the key barrel 18 is rotated to actuate the bolt mechanism upwardly as viewed in Figs. 2 and 3. The slots 27 do not register with the bolts 26 15 when the switches are in positions other than those in which it has been arranged to lock them. In case no notch 27 is in register with either of the bolts 26, the corresponding bolt, or bolts, as the case may be, is pressed 20 into the casing 24 against the force of the spring 30. When the respective switches are actuated into such position that one of the notches 27 registers with the corresponding bolt 26, the spring 30 forces it into locking 25 position, and further rotation of the switch is prevented.

It will be understood, however, that it is not possible to actuate the lighting switch through one of its locking positions to another locking position if the bolt mechanism is in operative position.

By means of this arrangement, it is unnecessary to maintain the key in the lock to maintain the ignition circuit in operation, as is necessary in connection with ignition switches of the usual type. The key may be removed when the locking mechanism is in either its operative or its inoperative position. When the key is removed 30 with the locking mechanism in operative position, it is only necessary, upon leaving the vehicle, to actuate the ignition switch to its "Off" position. If the lighting switch is in its "Off" position, it will have been 35 locked prior to the withdrawal of the key. If the headlights are in use, the lighting switch may be moved to the position designated "Aux. Rear" which is the usual position for parking. If the lighting system is 40 in use, the locking mechanism must be in inoperative position to permit the adjustment of the lighting switch to its "Off" position.

The above and other advantages will be apparent to those familiar with the art of 45 operating motor vehicles.

I claim as my invention:

1. The combination with a plurality of 50 movable switch members, each having a plurality of positions, of a locking mechanism comprising two relatively movable engaging members, said mechanism having two positions in one of which the respective switch members are automatically locked upon their actuation to predetermined 55 positions.

2. The combination with a plurality of 60 movable switch members, each having a plurality of positions, of a locking mechanism comprising two relatively movable members for engaging said switch members, 65 said mechanism having two positions in one of which the respective switch members are locked when they occupy predetermined positions.

3. The combination with a locking mechanism 70 comprising a movable member and a plurality of members carried thereby and biased to extended positions relatively thereto and means for actuating said movable member into and out of operative position, 75 of a plurality of switch members to be respectively engaged by said biased members when the locking mechanism is in operative position and the several switch members occupy predetermined positions. 80

4. The combination with a locking mechanism 85 having a movable member and a plurality of members carried thereby and independently biased to certain positions relatively thereto and means for controlling 90 the position of said mechanism, of a plurality of switch drums having portions coacting respectively with said biased members to lock said drums when the locking mechanism is in an operative position and the respective drums occupy predetermined positions. 95

5. The combination with a pair of rotatable switch members in substantially the same plane, each of said members having 100 engaging portions corresponding to certain positions, of a locking mechanism comprising a pair of relatively movable elements for engaging the said portions of the respective switch members, a member for carrying 105 said elements and means for yieldingly retaining said elements in engaging position.

6. The combination with a pair of rotatable switch drums in substantially the 110 same plane, each of said drums having recesses corresponding to certain positions of said drums, of a locking mechanism comprising a movable member, a pair of elements yieldingly supported by said movable member for respectively co-acting with the recesses of the several drums. 115

7. The combination with a pair of rotatable switch drums in substantially the same plane, each of said drums having recesses corresponding to certain positions of 120 said drums, of a locking mechanism comprising a movable member, a pair of elements supported by said movable member for coacting with said recesses, means for actuating said movable member into and out of operative position and means for yieldingly permitting movement of said elements relatively to the movable member in case 125 said recesses do not register with said ele- 130

ments when the latter are in operative position.

8. The combination with a pair of rotatable switch drums each having a plurality of positions and notched portions corresponding to certain of said positions, of a locking mechanism comprising a pair of elements for respectively coacting with the switch drums to lock them in said certain positions, a member for supporting said elements and for moving them into and out of operative positions and means for yieldingly permitting movement of said elements relatively to the supporting member in case said notched portions do not register with said elements when the latter are actuated to their operative positions.

9. The combination with a pair of rotatable switch drums each having a plurality of positions and notched portions corresponding to the "Off" position of one of said switch drums and to the "Off" position and an operative position of the other switch drum, of a locking mechanism operable to automatically lock each of said switch drums in one of said certain positions upon their respective actuation thereto while the locking mechanism occupies its operative position.

10. The combination with an ignition switch and a lighting switch, of a locking mechanism comprising a yieldingly supported locking element for each of said switches, said switches being provided with notches for coacting with said elements and corresponding to the "Off" position only of said ignition switch and to the "Off" posi-

tion and an operative position of the lighting switch whereby each of said switches is automatically locked in one of said positions upon their respective actuation thereto while said locking mechanism is in operative position.

11. The combination with a plurality of movable switch members, of a locking mechanism therefor comprising a key-actuated member, a plurality of members carried by said key-actuated member for coacting with said switch members, said coacting members being movable relatively to each other and to said key-actuated member, and means for yieldingly maintaining said coacting members in extended positions.

12. The combination with a plurality of movable switch members, of a locking mechanism therefor comprising a key-actuated member, a plurality of members carried by said key-actuated member for coacting with said switch members, said coacting members being yieldingly movable relatively to each other and to said key-actuated member whereby said locking mechanism may be actuated to locking position prior to the actuation of said switch members to their respective positions in which they are to be locked and each of said coacting members automatically engages the corresponding switch member upon its reaching the desired position.

In testimony whereof I have hereunto subscribed my name this 4th day of January 1922.

CHARLES W. LOVELL.
